REVERSIBLE COMBUSTION-ENGINE.

1,333,416.

Specification of Letters Patent.

Patented Mar. 9, 1920.

Application filed February 23, 1917. Serial No. 150,532.

To all whom it may concern:

Be it known that I, PAUL HENTSCHE, a subject of the Emperor of Germany, and a resident of St. Louis, Missouri, have invented the following-described Improvements in Reversible Combustion-Engines.

The invention is directed particularly to the means for reversing the valve gear of pumping apparatus in internal combustion engines or of other reversible machines whereby it is adapted to either direction of running, and the object of the invention is more especially to accommodate the scavenger pump of large size two-cycle marine engines to opposite directions of engine operation with least complication of structure and by means of parts occupying small space and not entailing enlargement of the over-all dimensions of the engine or its 10 crank shaft, on which account the principles of the present invention are particularly applicable in reversible engines for submarine propulsion. The invention consists broadly in the manner of application of a single link 15 eccentric motion to the control of the pump valve gear as explained below in connection with the illustration of the form at present preferred and which is shown in the accompanying drawings, wherein:

30 Figure 1 represents a vertical section through the scavenger pump of an internal combustion engine with parts in elevation;

Fig. 2 represents a similar view of the link motion of Fig. 1 in a different position;

Fig. 3 is a side elevation of the valve gear and the link motion as viewed from the right hand of Fig. 2 on line III—III.

Fig. 4 is a top plan thereof, on line 40 IV—IV.

The crank shaft marked 1 is to be understood as representing the main crank shaft of a marine internal combustion engine, such for example as a Diesel engine, the combustion cylinders of which are omitted or concealed by the pump structure. Through its connecting rod 2 this crank shaft drives a double-acting two-story scavenger pump of which the two pistons are marked 3 and the 45 pump cylinders 4. This pump mechanism is ordinary in principle and need not be explained. The several valve ports to the pump cylinders are controlled by a two-story piston valve 5 which reciprocates in a 50 valve casing 6 at one side of the pump cyl-

inders and the function of which is also that of ordinary pump valves. The said valve is reciprocated by its valve rod 7 from a rocker lever 8 the latter being fulcrumed by its sleeve 8^a on a shaft bearing 9 and it 60 will be understood that in the operation of the said pump valve, appropriate air inlet ports are opened to the suction sides of the two pump pistons for each direction of their reciprocating movement. These various 65 ports and passages are not completely illustrated in the drawings and do not require description, inasmuch as valve mechanism of any type, whether reciprocating or oscillatory, may be the subject of control according to the principle of this invention.

In order that the pumping apparatus shall not pump in a reverse direction on the reversal of the direction of engine rotation, the timing of the valve functions requires 70 to be reversed or shifted with relation to the angular position of the engine crank shaft, so that in either direction of running the open inlet passages shall always be in communication with the suction side or sides 75 of the pump pistons. For this purpose the inner arm 10 of the rock lever 8 is pivoted to a small block or blocks 11 slidingly contained in the groove or grooves of an oscillating link 12. This link, which is in effect 80 a lever, is fulcrumed on a bearing at 13 and connected at 14 to an eccentric strap 15, the latter embracing an eccentric 16 or equivalent member fixed on the engine shaft. Assuming the fulcrum 13 to remain in the position indicated in any of the figures of the drawing, it will be apparent that the rotation of the crank shaft and its eccentric will rock the link 12 and thereby rock the 85 rocker lever 8—10 and that the latter will 90 reciprocate the pump valve 5, and further that the angle of the eccentric can be so located on the crank shaft that the valve will reciprocate properly as a pump valve for the appropriate direction of crank shaft 95 rotation and with the parts in the position stated.

The fulcrum 13 of the link 12 is carried on a pair of similar stanchions 17 sleeved to the crank shaft one on each side of the eccentric 16, and joined at their upper ends by the cross bolt constituting said fulcrum 13, and also by a cross bolt or brace 18 which extends through a slot in the link and by still another cross brace or bolt 19 which is 11

located at the extreme upper ends of the stanchions. The two stanchions thus constitute a rigid but light supporting structure for the link 12 and which is directly carried by the crank shaft, or pump shaft and which can be turned or swung on the crank shaft to carry the link from one side to the other. In order that the said link-supporting structure may be retained firmly in either of its extreme positions, its upper end is connected to an oscillating spring plunger device 20 which may be regarded as any suitable means for holding or urging the said structure to its extreme position on either side, or for insuring a full throw of the structure to either side with what might be called a snap action. In the present case this snap action device consists of a spring seat 21 carried by trunnions in a bracket 22 fixed to the pump structure. The lower end of the plunger 20 is pivoted to the cross bolt 19 of the stanchion structure and its other end slides into and through the trunnioned spring seat 21. The spring surrounding the plunger urges it to its distended position and thereby presses the link-supporting structure to the limit of its permitted movement, to right or left as the case may be and assists such movement after the cross bolt 19 passes the line of centers between the spring seat trunnions and the crank shaft.

The stanchion structure is shifted by its link 23 which is connected by a lost motion slot 24 to a crank arm 25 on the rock shaft 9—the same rock shaft which forms the fulcrum bearing for the lever sleeve 8. This shaft 9, by means of its other arm 26 (Fig. 3) and a link connection 27 (shown in dotted lines in Fig. 1) is connected to a shaft 28 (top of Fig. 1) which may be understood to be the engine reversing-shaft controlling the valves of the combustion cylinders. The reversal of the engine valves thus, through these connections and the link 12 automatically throws the stanchion structure from one side to the other, swinging it on and concentrically to the crank shaft on which it is mounted as above described. The limit to its movement may be prescribed by the operating link connections 23, 24, 25, etc., or by some fixed member supplied for the purpose. In the movement of the link 12 when shifted from one position to the other the blocks 11, pivoted to the end of the rocker lever arm 10, travel relatively through the length of the link slot or slots to the opposite end thereof, in which position they are on the opposite side of the fulcrum 13 so that the arm now receives an oscillation which may be said to be opposite to that which it receives in the first described position of the link. The link 12 also carries with it the eccentric strap 15 which, in so moving, rotates on its eccentric 16 and the entire structure in the case shown, shifts from an angle

30° to one side of vertical to an opposite angle of 30° on the opposite side. By such change in the relation of the link to the angular position of the eccentric and the position of the rocker lever, the latter is caused to reciprocate its pump valve in the same relation to the crank shaft as before and notwithstanding the reversal of direction of the latter; that is to say, the pump continues to pump the scavenging air or whatever fluid it operates on in the same direction as formerly.

While the details of the structure above described are obviously subject to variation according to the option of the manufacturer, so it is preferred to mount the stanchions on opposite sides of the eccentric and join them by cross bolts or braces as above described, inasmuch as thereby the eccentric serves to determine their position on the crank shaft and with such construction it is convenient and also desirable to form the link block 12 as a divided member with opposed internal slots and accordingly to form the blocks 11 in two parts one occupying each slot and with the end of the rocker lever arm 10 between them. It is likewise preferred to mount the described structure directly on the crank shaft which drives the pump whether that be the engine crank shaft or a lay shaft and when it is mounted on the engine crank shaft as intended to be shown in the present case, it will be apparent that the entire structure is in position to be well lubricated and that it is likewise readily accessible by removing the crank case side plates, and it will be further noted that the entire structure is not only capable of being housed compactly in the crank case but that it occupies a space on the crank shaft, between the pump crank 30 and the shaft bearing 31 which is no wider than would be requisite if no such structure were employed. Consequently it will be plain that the reversal of the valve gearing according to the present invention is accomplished without extending the over-all length of the crank shaft or engine.

Claims:

1. In a reversible machine of the kind referred to, the combination with a pump shaft and pump mechanism driven thereby, of a reversible pump valve gear comprising a link connected to said valve gear, a single eccentric connected to the pump shaft to drive said link and means for changing the angular position of said link relatively to said shaft to accommodate said gear to the reverse rotation of the pump shaft.
2. In a reversible machine of the kind referred to, the combination with a pump and valve, of a machine-driven shaft to operate the latter, valve gearing between said shaft and valve, and a single eccentric carried by the shaft for driving said gearing, said gear

ing being subject to change of angular relation with respect to said shaft corresponding to the direction of rotation thereof.

3. In a reversible machine of the kind referred to, the combination with a pump crank shaft and pump mechanism driven by it, of a reversible pump valve gear comprising a link motion solely carried by said crank shaft and adapted to be swung to different angular relations thereon while retaining operative control of the pump valve, and a single eccentric on said shaft for driving said link motion during rotation of said shaft in both directions.
- 15 4. In a reversible internal combustion engine, the combination with an engine-driven pump mechanism of a reversible pump valve gear therefor comprising a single eccentric, a link member connecting the same to the pump valve, a fulcrum for said link stationary during the rotation of said eccentric, and means for changing the angular relation of said link member relatively to the said eccentric to accommodate reverse engine running.

- 25 5. The combination in a reversible internal combustion engine of a pump driven from the engine crank shaft and having valve gear also operated by said shaft and including a single eccentric link motion having an eccentric on the engine crank shaft, and a link and a fulcrum therefor stationary during the rotation of said shaft, said link and fulcrum being adapted to be swung angularly with relation to said shaft and eccentric to reverse said valve gear on reversal of the engine.

6. The combination in a reversible internal combustion engine, of a pump driven by the engine crank shaft and having valve gear also operated by said shaft, said gear including a single eccentric, and a link motion having a stationary fulcrum member carried by said engine crank shaft provided with means for swinging it thereon to reverse the timing of the valve function of the pump.

7. The combination in a reversible internal combustion engine, of an engine reversing shaft, a pump driven by the engine crank shaft having valve gear also driven thereby, said gear including an eccentric, a link driven thereby, and a fulcrum for said link carried concentrically to the engine crank shaft and adapted to be angularly shifted by the operation of said engine-reversing shaft.

8. In apparatus of the kind referred to the combination of a valve-operating lever, a shaft carrying an eccentric, a link connecting said lever and eccentric and a fulcrum for said link concentrically mounted with respect to said shaft and adapted to be swung about the same to reverse the valve timing.

9. In apparatus of the kind described, a pump and its valve, a single eccentric mechanism for operating the pump valve, said

mechanism being shiftable to reverse the timing thereof, and means acting on said mechanism to impart a snap action to the shifting movements thereof.

10. In apparatus of the kind described, the combination with an engine crank shaft, a pump operated thereby and a pump valve, of an eccentric on the engine shaft operating said valve, the operating connections thereof comprising a shiftable link member co-operating with a fixed valve rocker lever and mounted on a pair of stanchions, one of which is carried on the engine crank shaft on each side of the eccentric thereon.

15 11. In a reversible machine of the kind referred to, the combination with a pump and its valve and the driven shaft for operating the latter, of valve gearing between said shaft and valve including a link, a single eccentric on said shaft for oscillating the link, a fulcrum support for the link mounted concentrically with the shaft, and reversing means for shifting the fulcrum support and link.

20 12. The combination in a reversible internal combustion engine of a pump driven by the engine crank shaft and having valve gear also operated by said shaft, said gear including a single eccentric on the shaft, a link operated by said eccentric, a fulcrum support for the link pivotally mounted upon the shaft, and means for swinging said fulcrum support and with it the link to reverse the timing of the valve function of the pump.

25 13. In apparatus of the kind referred to, the combination of a valve-operating member having a block, a shaft carrying an eccentric, a link operated by said eccentric and having a channel engaging said block, a fulcrum support for the link concentrically mounted with respect to said shaft and adapted to be swung about the same to reverse the valve timing, and snap-over mechanism connected with said fulcrum support.

30 14. In a reversible machine, the combination with a rotary shaft and a reciprocating rod driven thereby, of a reversible gear for said rod comprising a link, a fulcrum therefor stationary during the rotation of said shaft and means for moving said fulcrum to accommodate the reversal of rotation of the shaft, and an eccentric on said shaft driving said link.

35 15. In a reversible machine, the combination with a machine driven shaft and a valve operated thereby, of a reversible valve gearing for said valve comprising a link, a fulcrum therefor stationary during the rotation of said shaft and means for moving said fulcrum to accommodate said valve to the reverse rotation of the shaft, and an eccentric driven with said shaft and driving said link.

40 16. In a reversible machine of the kind referred to, the combination with a pump and

- its valve, of a machine driven shaft, an eccentric thereon to operate said valve, and valve gearing between said eccentric and valve including a link and a fulcrum for said link stationary during the rotation of said shaft, said link being subject to change of angular relation with respect to said shaft corresponding to the direction of rotation thereof.
- 10 17. In a reversible machine of the kind referred to, the combination with a pump crank shaft and pump mechanism driven by

it, of a reversible pump valve gear comprising a link and a fulcrum for said link carried by said crank shaft and stationary during the rotation thereof, said link being adapted to be swung to different angular positions on said shaft while retaining operative control of the pump valve, and an eccentric on said shaft to drive the link.

15 20 In testimony whereof I have signed this specification.

PAUL HENTSCHE.
